Specification for Design.

Patented Feb. 28, 1922.

Application filed August 19, 1921. Serial No. 493,757. Term of patent 3½ years.

To all whom it may concern:

Be it known that I, AXEL E. JOHNSON, a citizen of the United States, residing at Muskegon, in the county of Muskegon and State of Michigan, have invented a new, original, and ornamental Design for a Step Tread, of which the following is a specification, reference being had to the accompanying drawings, forming a part thereof, in which—

Figure 1 is a top plan view of a step tread showing my new design; and

Figure 2 is a cross sectional view of the same taken on a vertical plane corresponding to line 2—2 of Figure 1.

I claim:

The ornamental design for a step tread substantially as shown.

AXEL E. JOHNSON.
